UNITED STATES PATENT OFFICE.

JAMES E. DESPAIN, OF TACOMA, WASHINGTON.

AUTOMATIC PIPE-CLAMP.

1,149,034.

Specification of Letters Patent.

Patented Aug. 3, 1915.

Application filed March 26, 1915. Serial No. 17,268.

To all whom it may concern:

Be it known that I, JAMES E. DESPAIN, a citizen of the United States, residing at Tacoma, in the county of Pierce and State 5 of Washington, have invented a new and useful Automatic Pipe-Clamp, of which the following is a specification.

This invention relates to pipe clamps, and more particularly to that class employed in 10 clamping or gripping well tubing or pipes.

An object of the invention is to provide an automatic pipe clamp as mentioned, capable of being readily assembled about a pipe to positively hold the same against any 15 undesirable downward movement; also to provide a clamp having a novel arrangement of jaw lifting levers.

Another object of the invention is to provide an automatic pipe clamp having its 20 gripping jaws so constructed as to allow them a maximum longitudinal movement, to thereby enable one set of jaws to grip several different sizes of pipe.

A further object of the invention is to 25 provide an automatic pipe clamp of general improved construction, whereby the device will be simple, durable and inexpensive in construction, as well as convenient, practical, serviceable and efficient in its use.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed can be made within the scope of what is claimed without departing from the spirit of the invention.

The invention has been illustrated in its 40 preferred embodiments in the accompanying drawings, wherein—

Figure 1 is a side elevation of the invention depicting it holding a well tubing. 45 Fig. 2 is a top plan view of the invention. Fig. 3 is an end view of the invention; and Fig. 4 is a sectional view taken on the line 4-4 of Fig. 2, showing the gripping jaws in two extreme positions.

In carrying out the present invention, 50 there is provided a casing or sleeve composed of two semi-circular sections 1 from which extend radial attaching ears 2. These ears have apertures for the reception of bolts 3 which hold the two semi-circular members 1 assembled to define a circular casing,

which has formed adjacent its lower end a base or platform 4.

Each section 1 of the circular casing is provided with a plurality of uniformly spaced slots or recesses 5, the inner walls of which are inclined as indicated at 6, to thereby impart to the slots 5 a wedge-shape. Extending laterally from each slot 5, adjacent and parallel with the inclined wall 6, are 60 two grooves 7 for the reception of keys or splines 8 which extend laterally from each side of a wedge-shaped gripping jaw 9. These jaws are received by the slots 4 and held slidably therein by the engagement of 65 the splines 8 with the grooves 7. The splines 8 extend throughout the entire length of the jaws 9 in order to allow the jaws a maximum longitudinal movement, thereby enabling one set of jaws to grip 70 several different sizes of pipes.

In order to manually raise the gripping jaws 9 to inoperative position, there is provided a lever 10, which is fulcrumed intermediate its ends, as at 11, upon the upper 80 end of a link 12, which has its lower end pivotally secured to the ear 2, by means of bolts 13 or other securing elements. The lever 10 has its inner end bifurcated to form two arcuate arms 14 which are pivotally secured, as at 14' to two complementing arcuate arms 15 extending from a lever 16 that is pivotally mounted, as at 17, to the upper end of a link 18. This link 18, is in turn, pivotally connected to the ears 2 at one side 85 of the casing 1, by means of a bolt 19, or other securing device. The arcuate arms 13 and 15 of the bifurcated levers 10 and 16 are provided with apertures 20 that loosely receive the upper ends of depending hooks or 90 links 21, which support, at their lower ends, 95 the gripping jaws 9.

In practical operation, the device is assembled about a well tubing T, as indicated in Fig. 1 of the drawings. In this position, 100 the well tubing may be moved upwardly, should such action be desired, without hindrance from the device, because the tubing sleeve or joint J will upon contact with the jaws 9, cause them to recede in their wedge-shaped slots, sufficiently to allow the joints to pass freely therebetween. But should the tubing accidentally start to descend, such action would cause the gripping jaws 9 to move downwardly and inwardly to thereby 105 securely grip the tubing against any further movement. In order to lower the tubing to

the bottom of the well, it is lifted sufficiently to release the grip of the toothed jaws 8, then the outer or handle end of the lever 10 is pressed downwardly, which causes the bifurcated ends of the levers 10 and 16, also the links or hooks 21 and jaws 9, to move upwardly. At this time, the jaws 9 have again receded sufficiently to allow the free passage of the tubing T and joints J therebetween, so that the tubing may be lowered. The jaws 9 are provided with splines or keys 8, that extend throughout their entire length, thereby permitting the maximum longitudinal movement of the jaws 9 within the slots 4, thus enabling one set of jaws 9 to hold several different sizes of pipe, as shown in Fig. 4. But should a tubing be encountered that the jaws then in the casing would not accommodate, a new set of jaws may readily be employed by merely removing the hooks or links 21 from the eye at the top of the jaws 9, thereby allowing their removal, preparatory to inserting another set of jaws.

This clamp may be removed from about the tubing by releasing the bolts 13, 19 and 14, which allows the entire jaw lifting device to be disassembled, after which the bolts 13 are removed to permit the casing 1 to be disassembled.

Having thus described the invention, what is claimed as new is:

1. In a device of the class described, a casing having wedge-shaped slots formed therein from which laterally extend inclined grooves; attaching ears secured to said casing; links pivotally secured to said attaching ears; levers fulcrumed on the links, said levers being pivotally united; hook-shaped links loosely secured to said levers; toothed wedge-shaped gripping jaws loosely secured to and suspended by the hook-shaped links, said jaws slidably received by the wedge-shaped slots; splines formed

along the inclined edges of the wedge-shaped jaws throughout the entire length of the jaws, said splines to slidably engage the laterally extended inclined grooves formed in the casing. 45

2. In a device of the class described, a circular casing composed of two semi-circular members, said members having upright wedge-shaped slots formed therein, from which extend inclined lateral grooves; diametrically opposed attaching ears radially extending from the periphery of the casing, 50 said ears being united by securing means; upright links pivotally secured to said ears; levers fulcrumed on the links, said levers being bifurcated at their inner ends; arcuate arms extending inwardly from the levers, 55 said arms being pivotally united; hook-shaped links loosely secured to the free terminals of said arcuate arms; toothed wedge-shaped gripping jaws slidably suspended in the wedge-shaped slots of the circular casing from the lower end of the hook-shaped links; and lateral splines extending from both sides of the wedge-shaped jaws, 60 said splines extending throughout the entire length of the jaws. 65

3. In a device of the class described, a casing having wedge-shaped slots from which grooves extend laterally, attaching ears secured to the casing, pivotally connected levers, link connections between the ears 75 and levers, toothed gripping wedges suspended from the levers, and slidable within the slots, and means upon the wedges for sliding within the grooves. 70

In testimony that I claim the foregoing as my own, I have hereto affixed my signature in the presence of two witnesses.

JAMES E. DESPAIN.
